UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

DRILLING MECHANISM

Application filed October 27, 1924. Serial No. 746,242.

My invention relates to drilling mechanisms.

An object of my invention is to provide an improved drilling mechanism. Another object of my invention is to provide improved hole cleansing means for such a mechanism. Still another object of my invention is to provide improved controlling means for the fluid distribution valve of a pressure fluid percussive drilling mechanism whereby the distribution valve may be held in one position to direct the flow of pressure fluid only to the forward end of the motor holding the hammer piston in its extreme rearward position and directing a supply of pressure fluid to the hollow drill steel to cleanse the hole. Still another object of my invention is to provide improved pressure fluid operated means for controlling the distribution valve of a drilling mechanism to accomplish the above function. These and other objects and advantages of my invention will, however, herein-after more fully appear.

In the accompanying drawings I have shown for purposes of illustration two forms which my invention may assume in practice.

In these drawings,—

Fig. 1 is a side elevation of a drilling mechanism in which my improved valve controlling and hole cleansing means is embodied, the view being shown partially in central longitudinal vertical section.

Fig. 2 is an end elevational view of the mechanism shown in Fig. 1.

Fig. 3 is a developed longitudinal sectional view taken substantially on line 3—3 of Fig. 2.

Fig. 4 is a sectional view similar to that shown in Fig. 3 of a modified form of construction.

In the illustrative form of my invention shown in Figs. 1 to 3 I have shown a drilling mechanism, generally designated 1, comprising a cylinder 2 having a bore 3 in which

a hammer piston 4 is reciprocable. The hammer piston 4 is provided with a forwardly projecting striking bar 5 adapted to actuate a hollow drill steel 6 carried by the forward end of the drilling mechanism, in a well known manner. The forward end of the cylinder 2 is adapted to have intermittent communication with the bore of the drill steel 6 and which communication is controlled by the striking bar 5 which is provided with the usual drill steel rotation flutes 5a. The upper surface of the cylinder 2 has a valve chest 7, of a well known form, formed thereon having a longitudinally extending bore 8 formed therein adapted to receive oppositely disposed sleeves 9 and 10 of identical construction. The sleeves 9 and 10 are each provided with stepped bores 11 and 12, the bores 11 having their outer ends closed by usual vented buffer plugs 13 and 14. The sleeves 9 and 10 and buffer plugs 13 and 14 are held in operative assembled relation by means of the usual transverse springs 15 and co-operating side rods 16, in a well known manner.

A fluid distribution valve 17, herein of the well known three-spool differential type, is disposed within the bores 11 and 12 formed within the sleeves 9 and 10 and is adapted to alternately control the supply of pressure fluid to the drilling motor from a suitable supply passage 18 by means of passages 19 and 20 communicating with the opposite ends of the cylinder and to alternately control the exhaust from the opposite ends of the cylinder through the passages 19 and 20 by means of passages 21 and 22 communicating with the atmosphere, in the usual manner. Usual valve throwing or kicker passages 23 and 24 are provided which communicate at longitudinally spaced points with the cylinder bore 3 and with the bores 11 at the opposite ends of the valve 17 by means of passages 25 and 26 formed in the sleeves 9 and 10 respectively. A throttle valve, generally designated 27, of any

50

65

70

75

80

85

90

usual form, is provided to control the flow of pressure fluid from a supply connection 28 through passages, not shown, to the supply passage 18 formed in the valve chest, in a well known manner.

5 In my improved construction it will herein be observed that the valve chest 7 is provided with a laterally projecting boss 29 within which a longitudinally extending bore 30 is formed, the bore 30 being disposed parallel 10 to the longitudinal axis of the valve 17. Ports or ducts 31 and 32 connect the opposite ends of the bore 30 with the pressure fluid supply passage 18 and with the front bore 11, respectively. A cylindrical slide valve or 15 plug 33 is disposed within the bore 30 and is provided with a stem 34 and an operating member or push button 35 conveniently located at the rear end of the machine adjacent 20 the throttle valve 27. A spring 36 encircles the stem 34 and is disposed between the push button 35 and the rear surface of the boss 29 and this spring normally tends to hold 25 the valve 33 in its extreme rearward inoperative position. As illustrated the valve 33 is provided with a circumferential groove 37 and a central passage 38 connecting the groove with the forward end of a bore 30. It will be noted that the buffer plugs 13 and 14 30 have usual restricted vent passages 39 formed centrally therein for exhausting the bores at the ends of the valve 17 to atmosphere in a well known manner. During normal operation of the drill, pressure fluid flowing from 35 the inlet passage 18 is distributed by the valve 17 alternatively to the opposite ends of the cylinder bore 3 through the passages 19 and 20. Simultaneously the valve 17 alternatively connects the opposite ends of the cylinder bore 3 to atmosphere through the passages 19 40 and 20 and exhaust ports 21 and 22. Consequently the hammer piston 4 is reciprocated thereby imparting a series of impacts to the shank of the drill steel 6. The valve 17 is 45 reciprocated by means of pressure fluid flowing from the cylinder bore 3 through the throwing passages 23 and 24 alternatively to the opposite ends of the valve 17, the valve alternatively engaging the buffer plugs 13 50 and 14 during operation thereof.

In the operation of this form of my improved valve controlling and hole cleansing means it will be noted that when it is desired to cleanse the drill hole the operator manipulates the push button 35 forcing the slide valve 33 forwardly within the bore 30 thereby bringing the groove 37 into communication with the port 31 and consequently admitting pressure fluid from the supply passage 18 to 55 the forward end of the bore 30. Pressure fluid then flows continuously from the bore 30 through the port 32 to the forward end of the bore 11 in the valve chest and acts on the forward end of the valve 17, overcoming the 60 throwing pressure at the rear end of the valve 65

and moving the valve rearwardly against the rear buffer plug 13, thereby holding the valve 17 in its extreme rearward position. Pressure fluid then flows from the passage 18 past the forward surface of the central spool of 70 the valve and through the passage 20 to the forward end of the cylinder bore. The pressure acting on the rear end of the piston 4 is exhausted to atmosphere at that time through the passage 19 and the passage 21. This 75 causes the pressure fluid within the forward end of the cylinder bore to hold the piston 4 in its extreme rearward position and consequently pressure fluid flows from the forward end of the cylinder bore 3 through the drill 80 steel rotation flutes 5^a formed in the striking bar 5 and hence through the hollow drill steel to cleanse the drill hole. When the push button 35 is released the valve 33 is returned to its inoperative position by the 85 spring 36 thereby closing the port 31. The valve 17 then resumes its normal fluid distributing function.

In the form of my invention shown in Fig. 4 it will herein be observed that the forward 90 buffer plug 14 is provided with a longitudinally extending bore 41 in which a suitable piston 42 is disposed, the diameter of the piston 42 being greater than that of the spools of the valve 17. The piston 42 is provided with a longitudinally rearwardly extending stem 43 adapted to engage the forward end of the valve 17. A reduced bore 44 is formed in the buffer 14 in which a spring 45 normally tends to hold the piston 42 in its 95 extreme forward inoperative position against the inner surface of a plug 46 which closes the forward end of the bore 41. The rear end of the bore 41 is vented to atmosphere by means of a small port 47. As illustrated the 100 rear buffer plug 13 is provided with a longitudinally extending port 48 which communicates with the bore 11 at the rear end of the valve 17 and with a laterally disposed bore 49 respectively, which is threaded engaged 105 at 50 by a valve casing 51. The valve casing 51 is provided with a longitudinally extending portion 52 in which a longitudinal bore 53 is formed and the portion 52 is secured at 54, herein preferably by brazing, to 110 a pipe connection 55 communicating with a radially extending port 56 which in turn communicates with the forward end of the bore 41 formed in the forward buffer plug 14. A cylindrical valve 57 is slidable in the 115 bore 53 and this valve is provided with a stem 58 and an operating member or push button 59 located in substantially the same position relative to the machine as the push button 35 shown in Figs. 2 and 3. A spring 120 60 encircles the stem 58 and is disposed between the valve casing 51 and the push button 59 and this spring normally tends to hold the valve 57 in its extreme rearward inoperative position. The valve 57 is provided with 125 65

a passage 61 which is adapted to connect the bore 49 formed in the plug 13 with the forward end of the bore 53 which communicates with the bore 41. The bore 53 is provided 5 with a laterally extending vent port 62 which is adapted to connect the forward end of the bore 41 with the atmosphere when the valve 57 is in its inoperative position. It will herein be noted that the stem 43 of the 10 piston 42 is flattened or cut away at 63 to vent the end of the valve 17 in the usual manner to the atmosphere through the bore 44 and 41 and the vent passage 47, this vent taking the place of the passage 39 described 15 in the first form of the invention.

In the operation of this form of my improved valve controlling and hole cleansing means it will herein be noted that when it is desired to cleanse the drill hole the operator 20 manipulates the push button 59, moving the valve 57 forwardly as indicated in Fig. 4, thereby opening communication between the bore 11 at the rear end of the valve 17, which bore communicates with the cylinder bore 3 25 by means of the throwing passage 23 and with the forward end of the bore 41 by means of a pipe connection 55. Pressure fluid then flows through the throwing passage 23, the chamber 11 at the rear end of the valve, the 30 passage 48, chamber 49, through passage 61 in the valve 57, through the pipe connection 55, and through port 56 to the bore 41, the fluid in the bore 41 acting on the piston 42, thus causing the latter to be moved rearwardly. The stem 43 engages the rear end of the 35 valve 17 at this time consequently causing the valve 17 to be moved rearwardly against the throwing pressure and to be held in its extreme rearward position against the rear 40 buffer plug 13. Pressure fluid then flows from the supply passage 18 past the forward surface of the central spool of the valve and through the passage 20 to the forward end of the cylinder bore 3. The pressure fluid 45 acting on the rear end of the piston 4 is exhausted to atmosphere through the passage 19 and the passage 21 at this time. This causes the pressure fluid within the forward end of the cylinder bore to hold the piston 4 50 in its extreme rearward position and pressure fluid then flows from the forward end of the cylinder bore by way of the usual drill steel rotation flutes 5^a formed in the striking bar 5 through the hollow drill steel to cleanse 55 the drill hole. When the push button 47 is released the pressure fluid in the forward end of the bore 41 is vented to atmosphere by way of the vent port 62 communicating with the bore 53 in the valve casing 51. Consequently 60 the spring 45 forces the piston 42 and the stem 63 forwardly to their inoperative position, the valve 17 again resuming its normal fluid distributing operation at this time.

65 As a result of my improvement it will

herein be noted that improved valve controlling and hole cleansing means is provided wherein the valve may be held in inoperative position and the flow of pressure fluid directed through the forward end of the motor 70 through the hollow drill steel to cleanse the hole. It will further be noted that improved pressure fluid actuated valve controlling and hole cleansing means is provided which is of an exceedingly simple and compact character 75 and which may be applied to a drilling mechanism of standard form with a minimum of change and expense.

While I have in this application specifically described two forms which my invention may assume in practice, it will be understood that these forms of the same are shown for purposes of illustration and that the invention may be modified and embodied in various other forms without departing from its spirit 80 or the scope of the appended claims.

What I claim as new and desire to secure by Letters Patent is:

1. In a rock drill, a cylinder, a piston in the cylinder, an extension on the piston having a passage therein positionable on rearward movement of the piston to establish communication between the forward end of the cylinder and a hollow steel which is positioned for actuation by the piston, a valve chest having a chamber and an inlet port, supply passages leading from the chamber to the cylinder on opposite sides of the piston, a valve in the chamber controlling the distribution of pressure fluid to the supply passages, 90 kicker passages leading from the valve chamber to the cylinder on opposite sides of the center thereof to control the movement of the valve, a bore in the valve chest, ducts leading from one end of the chamber and from the inlet port to the bore, a manually operable plug in the bore, said plug having a passage and ports communicating in one position of said plug with the ducts to move the valve to establish direct communication between the inlet port and the cylinder at the front end thereof and through the passage in the piston extension with a drill steel. 95

2. In a rock drill, a cylinder, a piston in the cylinder, an extension on the piston having a passage therein, a valve chest having a chamber, an inlet port in the valve chest in constant communication with the chamber, supply passages leading from the chamber to the ends of the cylinder, a valve in the chamber controlling the distribution of pressure fluid from the inlet port to the supply passages, a bore in the valve chest, ducts leading from one end of the chamber and from the inlet port to the bore, crossed kicker ports leading directly from the valve chamber to the cylinder on the opposite sides of the center thereof, a manually operable plug in the bore having a passage therein to 100 105 110 115 120 125 130

establish direct communication between the ducts independent of the kicker ports for conveying pressure fluid substantially under full line pressure from the inlet port to the end of the chamber to hold the valve immovable in the opposite end of the chamber, and permitting an uninterrupted flow of pressure fluid from the chamber into one end of the cylinder and through the passage in the extension to a drill steel.

In testimony whereof I affix my signature.
ELMER G. GARTIN.
